UNITED STATES PATENT OFFICE.

HENRY LOCKE, OF MARION, IOWA.

STALL.

SPECIFICATION forming part of Letters Patent No. 721,578, dated February 24, 1903.
Application filed July 5, 1902. Serial No. 114,477. (No model.)

To all whom it may concern:

Be it known that I, HENRY LOCKE, a citizen of the United States, residing at Marion, in the county of Linn and State of Iowa, have invented new and useful Improvements in Stalls, of which the following is a specification.

It is the present practice to so construct stalls that the partition which normally separates them may be partially withdrawn and rotated on an axis to a position transversely of the stalls, thus utilizing it as a closure for their front and converting two single open-front stalls into one large box-stall.

15 My invention relates to this class of devices, and has for its objects to provide improved mechanism for sustaining and manipulating the partition, whereby the construction of the device as a whole is materially simplified, the operation of the parts rendered easier and more rapid, and whereby the partition may be caused to assume an unobstructive position at the extreme rear of the stall should it at any time be desirable to 25 have the device serve functions other than that of a stall—such, for example, as the storage of vehicles or the like.

To these ends the invention comprises in a stall the combination, with a partition, of a 30 track or way, means sustaining the partition and adapted to travel on the track or way, and means whereby the partition may at will be turned to a position transversely of the track or way.

35 The invention further comprises the details of construction more fully hereinafter set forth.

In the accompanying drawings, Figure 1 is a front view of a stall embodying my invention, 40 the partition being in position to close the same. Fig. 2 is a perspective view illustrating the partition turned preparatory to insertion to form two stalls. Fig. 3 is a front view with the partition fully inserted and forming two 45 open-front stalls. Fig. 4 is a perspective view illustrating the partition in an unobstructive position at the rear of the stall. Fig. 5 is a side elevation, on an enlarged scale, of the partition-suspending mechanism and guide. 50 Fig. 6 is a front elevation, partly in section, of the parts shown in Fig. 5.

Referring to the drawings, 1 indicates a

stall having partially open or ventilated side walls 2 and a solid rear wall 3.

4 is a fore and afterwardly extending track 55 or way in the form of a metal bar, preferably suspended overhead near the top of the stall and sustained at its rear end by the back wall 3, to which it is attached in any suitable manner, and at its front by a metal 60 strap 5, suitably connected thereto and to a supporting and strengthening beam 6.

Suspended from the track 4 by means of a suitable framework 7, having journaled therein in caster-wheels 8, which travel on the track, 65 is the movable partition 9. This partition, which embraces in its general organization the end posts 10 and 11, an intermediate post 12, and a top horizontal bar 13, is swiveled to the framework 7 by means of a swiveling-pin 70 14, formed integral with a casting 15, securely bolted to the top bar 13 of the partition. By this construction it will be seen that the partition may not only travel to and fro along the track, but may, owing to its 75 swivel connection, be turned to any desired angle, and this at any desired point throughout the line of travel.

16 is a door let into the partition hinged to post 12 and adapted to close against post 80 10. This door affords access to the stall when its front is closed by the partition, as in Fig. 1, or as a means of communication between the two stalls when the partition is inserted, as in Fig. 3.

85 17 is a slot formed in the upper end of post 11 and adapted when the partition is inserted to embrace the end of track 4 and hold the partition against lateral movement.

18 and 19 are suitable catches for securing 90 the partition when closing the front of the stall.

In operation if desired to convert a single box-stall into two open-front stalls the catches 18 and 19 are released and the partition is turned on its swivel to the position shown in Fig. 2 and then shoved inward. To convert two stalls into one, the manner of procedure is reversed. If it is desired to employ the stall for the accommodation of vehicles or the like, the partition may be shoved directly back and lie flatly against the rear wall of the stall, as in Fig. 4.

It is to be understood that I believe myself

2
to be the first to produce a stall having a partition which travels to and fro on a track or way and which is susceptible of being turned at right angles to the track at any point in its line of travel. I do not, therefore, limit myself to the details herein shown and described, as the same may be variously modified without departing from the spirit or scope of the invention.

o Having thus described my invention, what I claim is—

1. In a stall, the combination of a partition having a post at one end with a vertical slot therethrough, a track or way disposed above 15 the partition and adapted to be engaged by the slot in the said post, means suspending the partition and adapted to travel on the

track or way, and means whereby the partition may, at will, be turned to a position transversely of the track or way.

2. In a stall, the combination with a partition, of an elevated track or way, means sustaining the partition and adapted to travel on the track or way, and means whereby the partition may be turned at right angles to the track at any point throughout the line of travel.

In testimony whereof I affix my signature in presence of two witnesses.

HENRY LOCKE.
